UNITED STATES PATENT OFFICE.

WILLIAM K. FLATT, OF DULUTH, MINNESOTA.

BICYCLE-SUPPORT.

SPECIFICATION forming part of Letters Patent No. 566,071, dated August 18, 1896.

Application filed April 20, 1896. Serial No. 588,289. (No model.)

To all whom it may concern:

Be it known that I, WILLIAM K. FLATT, a citizen of the United States of America, residing at Duluth, in the county of St. Louis 5 and State of Minnesota, have invented certain new and useful Improvements in Bicycle-Supports; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention has relation to improvements in bicycle-supports, and the object is to provide a support of the kind named and for the purpose intended which is simple and durable in construction, easily and readily manipulated, and efficient in operation and effects.

I have fully and clearly illustrated my invention in the accompanying drawings, wherein—

25 Figure 1 is a side view of a safety-bicycle having my invention applied thereto, the supports being shown moved down to sustain the bicycle in upright position. Fig. 2 is a detail view showing a part of the frame and the supports lifted to the position to which they are 30 carried when the wheel is in motion. Fig. 3 is a detail front view of the supports removed from the machine, and also showing in dotted lines the supports moved to their outward and downward limit into the position they assume 35 when so held. Fig. 4 is a detail perspective view of the latch for holding the lever. Fig. 5 is a plan view of the actuating-lever.

A designates a bicycle-frame of a well-known type, to which my invention is applied 40 and secured. To each of the crank-bars 1 2, adjacent to the crank-bracket, is rigidly secured a vertically-arranged sleeve 3 4, formed with a spirally-disposed slot 5. In the sleeves 3 4 are fitted the stems of the supports B B', 45 provided with studs b b^x, secured in the supports and projecting into the spirally-arranged slots of the sleeves, so that when the supports are moved down the engagement of the studs in the slots will rotate the supports 50 and turn the lower ends outward. The lower portions of the supports are curved, as at 7, and carry on their ends wheels 8 8^x, held in

stirrups 9, having their stems journaled in the ends of the supports.

It will be perceived that by changing the 55 direction of the spiral slots the supports may be made to operate with their curved portions standing to the rear and in the reverse to the position indicated in the drawings. To the saddle or top bar of the frame is fulcrumed a curved lever 10, the rear end of which is formed with bearings 11 11^x, consisting of open-end slots which take about the annular necks or grooves 12 in the upper ends of the supports. To the front end of 60 the lever 10 is secured one end of a spiral spring 13, the other end of the spring being suitably secured to the frame, substantially as shown; and to the top bar of the frame is secured a spring-catch 14, arranged in the 65 path of the lever 10 and formed with a thumb-piece 14^x for convenience in releasing the catch from engagement with the lever, so that when the lever has been moved to push the supports down to hold the machine erect 70 they will be held in such position by the engagement of the lever and the catch, the engagement being maintained by the force of the spring. To the front end of the lever is secured a cord or flexible wire 15, which is 75 led up through a guide-hole 15^a, as shown, and is provided with a hand-piece 15^x, by which the lever may be moved.

The supports may be made of any suitable material, and since they are of little weight 85 they will add but little to the weight of the machine, and being adapted to turn and stand closely together when not in use they take up but little room and do not in the least interfere with the movements of the rider or 90 the action of the machine.

The operation of the machine or device is as follows: When it is desired to dismount, or to use the supports while the rider is in the saddle, the cord 15 is pulled up until the 95 lever pushes down the supports and the lever engages with the catch. This movement at the same time has turned the supports on their axes, so as to place the wheels outward, and the machine will be thus supported in upright position. When the occasion for the use of the supports has passed, the catch is pushed from engagement with the lever and the force of the spring then automatically

lifts the supports and in their upward movement they are turned to swing the wheels into the normal position.

Having thus described my invention, what I claim, and desire to secure by Letters Patent, is—

The combination with a bicycle-frame, of the vertically-secured sleeves 3,4, formed with spirally-disposed slots 5, the supports B, B', 10 having studs b, b^x arranged in the slots of the sleeves, and forwardly-curved lower portions 7, wheels 8, 8^x, journaled in the ends of the supports, the curved lever 10 formed with

bearings to take the upper ends of the supports, a spring 13, secured to the front end 15 of the lever, the spring-catch 14, on the top bar of the frame, and a pull-cord 15, let through the top bar of the frame and provided with a handpiece, all arranged and combined to operate as specified. 20

In testimony whereof I affix my signature in presence of two witnesses.

WILLIAM K. FLATT.
